UNITED STATES PATENT OFFICE.

GROVER CLEVELAND TUCKER, OF TUSCALOOSA, ALABAMA.

DESIGN FOR A BODY FOR AN INSECT-DESTROYER.

51,818.

Specification for Design.

Patented Feb. 26, 1918.

Application filed April 28, 1917. Serial No. 165,285. Term of patent 14 years.

To all whom it may concern:

Be it known that I, GROVER C. TUCKER, a citizen of the United States, residing at Tuscaloosa, in the county of Tuscaloosa and State of Alabama, have invented a new, original, and ornamental Design for a Body for Insect-Destroyers, of which the following is a specification, reference being had to the accompanying drawing, forming part thereof.

Figure 1 is a view in side elevation of a body for an insect destroyer showing my new design;

Copies of this patent may be obtained for five cents each, by addressing the "Commissioner of Patents, Washington, D. C."

Fig. 2 is a view in top plan of the body as herein embodied; and

Fig. 3 is a view in front elevation of my body.

I claim:

The ornamental design for a body for an insect destroyer, as shown.

GROVER CLEVELAND TUCKER.
